INDICATING KNOB FOR FLOW CONTROL VALVE

Verne P. Donner, Palatine, Ill., assignor to Deltrol Corp.,
Bellwood, Ill., a corporation of Delaware

Filed July 11, 1966, Ser. No. 3,023

Term of patent 14 years

(Cl. D52—6)

The single figure is a perspective view of an indicating knob for flow control valve embodying my new design.

The undisclosed portion of the control knob is substantially the same in appearance as the portion shown.

The dominant features of my new design reside in those portions thereof illustrated by solid lines. The valve portion shown in broken lines is for illustrative purposes only.

I claim:

The ornamental design for an indicating knob for flow control valve, as shown and described.
